CUTTING DEVICE

Edward Francis Arnold, New York, N. Y.

Application June 29, 1950, Serial No. 171,089

10 Claims. (Cl. 30—2)

1

This invention relates to a cutting device, and more particularly to means for cutting cartons, packages, and the like from the interior thereof without damaging the contents. The present application is a continuation in part of my co-pending application Ser. No. 95,610 filed May 27, 1949, which issued on August 30, 1950, as Patent No. 2,573,381.

In said prior application I have referred to certain disadvantages of presently used carton openers. Such openers, it will be noted, cut the carton from the outside with the possible result of damaging the contents of the carton. In many instances, the blades in the holder may be fixed loosely to said holder with the result that there is a tendency upon continued use of the cutter for the blade to become loose and to cut the carton unevenly. Furthermore, when passing such a cutter over the edge of a carton, there may be a tendency for the blade during the cutting of the carton to extend into the interior of the container and damage the contents of said container.

In view of the above and other disadvantages, it is an object of my invention to provide a carton opener in which the blade or cutting portion of said opener adjustably extends from the handle of the opener and is disposed so that it operates from the interior of the carton being opened, with little or no damage of the contents of the carton being damaged.

It is another object of the present invention to provide a device of simple, compact and economical construction in which the cutting member forms a permanent and integral part of said device and is adapted to cut open a carton and the like from the interior thereof.

Still another object of the present invention is to provide a cutting device for cartons and the like in which the cutting member of the device is so disposed that it cuts the carton below the surface of the carton, said cutting being done from the inside out to avoid damaging the contents of the carton.

Still another object of the present invention is to provide an economically made, easily manipulable carton or box cutter having a sharp inclined cutting edge with a skid edge behind said cutting edge facing the contents of the carton without damaging the same when said cutter is in use.

A more specific object of my invention is to provide a cutting device for containers having a handle and an inwardly and upwardly inclined cutting edge adapted to penetrate a container and

2

cut the same from the interior out without damaging the contents thereof.

Other objects and advantages will become apparent from the following description taken in conjunction with the accompanying drawings, in which:

Fig. 1 is a perspective view of a preferred embodiment of the invention;

Fig. 2 is an end, sectional view showing the embodiment of Fig. 1 as applied to a container, showing the cutting of the container from the interior thereof;

Fig. 3 is a top plan view of Fig. 1 showing the embodiment in use against a wall of a carton;

Figs. 4, 5 and 6 show modifications of the blade shown in Fig. 1.

Referring now to the drawings in which like numerals refer to like parts throughout, there is provided a cutting device 10 containing a flat surfaced face piece or member 11. Connected to one side of said face piece 11 is a handle member 12 extending perpendicularly from said face piece and fixed thereto by means of a plurality of screw members 13 extending through said face piece 11 into said handle 12.

Said face piece 11 is provided with a sliding or surface contacting portion 14 adapted to form a sliding abutment or contact with the exterior 15 of a carton 16. Both said face piece 11 and handle 12 are provided with a suitable slot or groove 17 and 18, respectively, which are in alignment, as shown more clearly in Fig. 2. Said slots 17 and 18 are adapted to accommodate an adjustable blade member 19 so that the same extends perpendicularly from the face piece 11. Blade 19, as clearly shown in Figs. 1, 2 and 3, contains a skid or gliding edge 20 which is relatively smooth or beaded and has no cutting properties. Said blade 19, furthermore, is provided with cutting edges 21 and 22, respectively, which may preferably be beveled and are inclined with respect to both the skid edge 20 and the contacting surface 14, so that the cutting edges face the contacting surface 14. Intermediate

each of said cutting edges 21 and 22, respectively, and skid edge 20, there is provided an acutely formed recessed section 23 and 24, respectively. Said sections 23 and 24 form with cutting edges 21 and 22, respectively, sharp cutting or piercing points 25 and 26, respectively, to permit easy piercing or penetration of the wall 15 of carton 16.

Said cutting edges 21 and 22 terminate into and merge with a perpendicularly extending section or boss 27 provided with an elongated hole

28 so as to permit relative adjustment of said blade 19 with respect to the face piece 11 and handle 12. The boss is rigidly fixed to the handle 12 by means of cross retaining member 29 extending through said handle 12. Such relative adjustment of the blade 19 with respect to the handle and face piece permits for the cutting of cartons or other types of containers of any thickness. It is important to note that in the use of the device 10 the boss 21 should not extend outwardly beyond the contacting surface 14 of face piece 11, since it is desired to obtain a smooth, clean cut of the carton without rolling or accumulation of any of the cut material between the face piece 14 and the cutting edges 21 and 22.

In the modification shown in Fig. 4, it will be noted that I provide a differently shaped blade 30 containing only a single edge 31 extending at an incline from boss 32 to skid edge 31a. Said blade 30 has an elongated opening 33. In Fig. 5, I show a blade 33 similar in design to that shown in Figs. 1, 2 and 3 with the boss removed but having an elongated opening 38.

In Fig. 6, I provide a blade 34 similar in design to that shown in Fig. 5, but of substantially right angle formation containing an elongated opening 35 adjacent the short leg 36 of the triangle.

In the use of my invention, after the necessary adjustment of the blade has been made with respect to the handle and face piece, it is relatively easy to cut the carton by initially piercing the same by means of piercing points 25 and 26, thus permitting either cutting edge 21 or 22, depending upon the direction in which the device is moved with respect to the carton, to cut the carton wall in any manner. Between either cutting edge 21 or 22 and face contacting portion 14, there is effected a smooth relatively easy cut with no danger of tearing or rough edging of the carton as it is being cut.

By the use of the present invention any type of carton whether straight, such as boxes, or circular, such as cylinders, can be easily cut from the inside without damaging or scratching any of the contents of the carton. Furthermore, if any of the contents are in the way of the cutting device, the recessed sections 23 and 24 and skid edge 20 would push aside the contents while the cutting action is being performed. Also, the cutting can be effected in any direction or on any side of the carton wherever the cutting is desired. The face piece 11, which may be level, as shown, or circular in outline, acts as a guide for maintaining a steady even cutting action on the carton while the device is in use. In my type of invention, the blade is adjustably slidable and permits the cutting of cartons of any desired thickness or where the contents are relatively spaced with respect to the interior wall of the container or carton.

While several preferred embodiments of my invention have been described, it is understood that various modifications as to form, use and arrangement of parts and materials may be made without departing from the spirit and scope of the invention as claimed herein.

I claim:

1. A device for cutting open a container from the inside thereof, comprising a handle, a face member connected to said handle adapted to lie flush with the outer face of the container and a blade extending outwardly of the handle through the face member having an inclined cutting edge with a terminal piercing point for penetrating the

4
5 container and permitting cutting of the container from the interior thereof, said blade having an external skid edge spaced from the face member and leading to the terminal piercing point.

6 2. A cutting device for cutting open a container from the inside, comprising a handle, a slotted face member perpendicularly connected to said handle adapted to lie flush against the outer face of the container, and a blade retained by the handle and extending through said slotted face member, said blade having an inclined cutting edge facing the face member, said blade having a terminal receding piercing edge and a skid edge, said skid edge being adapted to lie against the contents of the container to prevent cutting or damage of the same.

7 3. A device for cutting open a container from the inside thereof, comprising a handle, a face member connected to said handle adapted to lie flush with the outer face of the container, and a blade having a central upwardly extending handle portion attached to the face member and a cutting edge on the blade sloping upwardly toward the face member, said blade further having a relatively smooth skid edge behind the cutting edge adapted to face the interior of the container and an acutely receding section connecting the skid edge and the cutting edge forming a cutting or piercing point to permit penetration of the edge into the interior of the container and cut the same.

8 4. A device for cutting open a container from the inside thereof, comprising a handle, a face member connected to said handle adapted to lie flush with the outer face of the container and a substantially triangular shaped blade having a central upwardly extending handle portion attached to the face member and a cutting edge on the blade sloping upwardly toward the face member, said blade further having a relatively smooth skid edge behind the cutting edge adapted to face the interior of the container and an acutely receding section connecting the skid edge and the cutting edge forming a cutting or piercing point to permit penetration of the edge into the interior of the container.

9 5. A device for cutting open a container from the inside of the same, comprising a handle, a face member connected to said handle adapted to lie flush with the outer face of the container, and an adjustably connected blade having a central extending handle portion attached to the face member and a cutting edge sloping toward the face member, said blade further having a relatively smooth skid edge behind the cutting edge adapted to face the interior of the container and an acutely receding section connecting the skid edge and the cutting edge forming a cutting or piercing point to permit penetration of the edge into the interior of the container.

10 6. A device for cutting cartons and the like from the inside thereof, comprising a substantially triangular shaped blade having an apical extending portion, a handle for retaining said extending portion, and a face piece intermediate the blade and the handle adapted to lie flush against the container as it is being cut open, said blade having a cutting edge sloping from the extending portion and a skid edge forming the base of the triangular shaped blade, said blade having a terminal recess in the apical portion thereof for interconnecting the handle and blade.

11 7. A device for cutting cartons and the like from the inside out, comprising a handle, a face piece connected to the handle adapted to lie flush

against the outer face of the carton and slide against the same, and a substantially triangular cutting blade extending perpendicularly from the face piece through the handle, said blade having a sloping cutting edge extending inwardly toward the face piece whereby the container is cut on the inside between the face piece and the cutting edge.

8. A device for cutting cartons and the like from the inside out, comprising a handle, a face piece connected to the handle adapted to lie flush against the outer face of the carton and slide against the same, and an adjustably connected blade extending perpendicularly from the handle through the face piece, said blade having a sloping cutting edge extending inwardly toward the face piece whereby the container is cut on the inside between the face piece and the cutting edge, said blade having a dull skid edge parallel with the interior wall of the carton and facing the contents without damaging the same.

9. A cutting device for opening containers from the interior thereof, comprising a face member, a handle connected with said face member and a substantially equilateral triangular shaped

blade with a plurality of cutting edges, said blade extending perpendicularly from said handle and face member, said blade further having its cutting edges inclined outwardly from the face member and being adapted to cut the interior of the container along the cutting edge adjacent the face member.

10. A cutting device according to claim 8 in which the cutting edge of the blade forms a terminal recessed angular section adapted to pierce the carton and permit entry of the blade into the interior of the carton and cut the same from the inside thereof.
